KARL HEINEMANN, OF DUSSELDORF, GERMANY, ASSIGNOR TO RHEINISCHE METALL-
WAAREN-UND MASCHINENFABRIK, OF DUSSELDORF-DERENDRÖF, GERMANY

AUTOMATIC FIREARM

Application filed July 22, 1930, Serial No. 469,795, and in Germany July 29, 1929.

My invention relates to a device for changing or altering the firing speed of automatic fire arms having a toggle-joint breech in which the closing spring acts, by means 5 of a pressure slide, in a well known manner, upon a locking lever of the toggle-joint. According to the present invention this pressure slide is wedge-shaped and may be inserted in different positions in its bearing 10 guide. The pressure slide acts, by means of a bearing surface inclined to the direction of its movement, upon the locking lever with a lever arm the length of which is altered on shifting, i. e. on turning the pressure piece around its axis of movement about 15 an angle of 180° for instance. Hereby the momentum of the force of the closing spring acting upon lengths of the toggle-joint is also altered, so that according to the insertion 20 of the pressure piece the opened breech is closed slower or quicker by the said spring as well as a greater or less resistance against opening is offered to the closed breech, whereby a different firing speed is obtained.

25 Preferably the point of attack of the toggle-joint locking lever upon the inclined surface of the pressure piece of the closing spring is arranged eccentrically to the pivot axis of the pressure slide, so that besides 30 altering of the effective lever arm simultaneously the tension of the closing spring is altered also.

35 In the accompanying drawing one embodiment of the invention is shown by way of example in connection with a toggle-joint breech.

Fig. 1 shows the toggle-joint in the stretched position on adjustment of the pressure piece of the closing spring for single firing as well as for slow permanent firing, 40 the position the toggle-joint occupies, when the breech is opened, is shown in dash and dotted lines in this figure, and Fig. 2 illustrates the several parts of the toggle-joint 45 in the stretched position after the pressure piece of the closing spring has been turned to effect quick permanent firing, the position the toggle-joint occupies, when the breech is opened, also being shown in this figure 50 by dash and dotted lines.

The breech consists in well known manner of the breech piece a , the toggle levers b_1-b_2 and the breech spring c . The breech spring c bears, by means of a pressure piece c_1 movably guided in the casing of the spring, 55 against a nose b_3 of the rear toggle lever b_2 which may be oscillated about the pivot b_4 arranged in the casing of the arm. Hereby the spring c forces the toggle-joint into the stretched position, so that the breech piece a comes into the locked position. The pressure piece c_1 is, for instance, guided by noses 60 c_3 which slide in guide notches c_2 of the spring casing and is thereby safely held against rotation. The front surface of the pressure piece c_1 is bevelled. If the pressure piece c_1 is inserted in its bearing guide in the position shown in Fig. 1, the closing spring at opened breech acts with the component P of its maximum force and with 65 a relatively short lever arm h to close the breech, and reversely the closing spring opposes with a longer lever arm h_1 a torque to the opening of the closed breech. Both actions together cause slow breech movements during firing and therefore a low 70 firing speed.

If, however, the pressure piece is adjusted by turning it around its axis of displacement about an angle of 180°, the closing 80 spring will, as the nose b_3 of the locking lever acts eccentrically to the shifting axis of the pressure piece upon the now turned inclined surface c_4 , at first be more tensioned, whereupon at opened breech the 85 component P_2 of the higher maximum force of the closing spring will act with a great lever arm h_2 , i. e. with a great torque, to close the breech, whereas a small momentum, acting with the very small lever arm h_3 , is 90 to be overcome to open the closed breech. In this case the breech movements at firing are effected substantially quicker than under the conditions according to Figure 1. Experiments made with the construction 95 shown have proved an increase of the firing speed of about 40%.

What I claim is:

1. In an automatic fire arm, a toggle-joint breech, a locking lever, a wedge shaped 100

pressure piece, capable of being inserted in different positions in a bearing guide, and a closing spring acting by means of said pressure piece upon said locking lever, so that by turning of said pressure piece the lever arm of the said closing spring, acting upon said locking lever, and therefore the firing speed will be altered.

2. In an automatic fire arm, a toggle-joint breech, a locking lever, a wedge shaped pressure piece, capable of being inserted in different positions in a bearing guide, and a closing spring acting by means of said pressure piece upon said locking lever, said pressure piece having an inclined surface and said locking lever working against said surface outside the pivot axis of said pressure piece, so that by the turning of said pressure piece an alteration of the effective lever arm and simultaneously an alteration of the tension of the closing spring are effected.

In testimony whereof I have affixed my signature.

KARL HEINEMANN.
